WATER PURIFIER

William H. Stephens and David R. Jones, Albuquerque, N. Mex., assignors to Water Pollution Control Systems, Inc., Dallas, Tex.

Filed Apr. 29, 1974, Ser. No. 464,777

Term of patent 7 years

Int. Cl. D23—01

U.S. Cl. D23—3

FIG. 1 is an exploded side elevational view of a water purifier showing our new design;

FIG. 2 is an exploded right end elevational view thereof;

FIG. 3 is a top plan view of the cover portion thereof;

FIG. 4 is a top plan view of the main portion thereof; and

FIG. 5 is a bottom plan view of the main portion thereof.

The intake suction hose is broken away in FIG. 2 to indicate indeterminate length and fragmentarily shown in FIGS. 1, 4 and 5 for convenience of illustration.

We claim:

The ornamental design for a water purifier, as shown and described.
